U.S. Cl. D7—88

FIG. 1

FIG. 4

FIG. 1 is a perspective view of the grill casing showing our new design in its closed position;

FIG. 2 is a side view of the grill casing in its open position;

FIG. 3 is a top view of the grill casing shown in FIG. 1; and

FIG. 4 is a side view of FIG. 3, the opposite view being a mirror image thereof but without the rectangular plug.

The grilling surface shown in broken lines in FIG. 2 is for illustrative purposes only and forms no part of the claimed design.

We claim:

The ornamental design for a casing for a grill, as shown and described.
